UNITED STATES PATENT OFFICE.

MOSES WILKES, OF TRENTON, NEW JERSEY.

COMBINED STEAM-PRESSURE GAGE AND DRAFT-REGULATOR.

SPECIFICATION forming part of Letters Patent No. 389,730, dated September 18, 1888.

Application filed December 22, 1887. Serial No. 258,693. (No model.)

To all whom it may concern:

Be it known that I, MOSES WILKES, a citizen of the United States, residing at Trenton, Mercer county, New Jersey, have invented 5 new and useful Improvements in a Combined Steam-Pressure Gage and Draft-Regulator, of which the following is a specification.

This invention relates to certain new and useful improvements in a combined steam-pressure gage and draft-regulator; and it consists, substantially, in such features of construction, arrangement, and combinations of parts, as will hereinafter be more particularly described.

The invention has for its object to provide 15 a combined steam-pressure gage and draft-regulator for steam-boilers, which shall possess all the advantages of simplicity of construction and cheapness of cost, and one also that shall effectually regulate the draft by which 20 to govern the steam-pressure and at the same time measure or indicate the pressure of steam in the boiler; and the invention has such other objects in view as will hereinafter more fully appear when taken in connection with the accompanying drawings, wherein— 25

Figure 1 represents a vertical sectional elevation of a combined steam-pressure gage and draft-regulator embodying my invention; and Fig. 2 is a side elevation thereof, partly in section. Fig. 3 is a horizontal sectional view 30 taken on the line $\alpha\alpha$ of Fig. 1.

In carrying my invention into effect I employ a suitable bed-plate having to one side thereof a vertical portion or wall, and to each 35 side of this plate is inserted a post between and by which is supported at the top a cross head or plate. Inserted in the bed-plate, about centrally of the posts, is a hollow stationary tube open at its upper end and communicating 40 at its lower end with the steam-pipe leading from the boiler, and surrounding such stationary tube is a vertically-moving tube closed at its top by a screw-cap, having projecting upwardly therefrom a stem, around 45 which is coiled a spring exerting a pressure between the cross head or plate and the screw-cap sufficient to maintain the outer vertically-moving tube normally downward, the said spring acting also to allow an upward movement of the tube by pressure of steam enter- 50

ing from the boiler. Surrounding the said outer tube, at or near its lower end, is a collar having a spindle carrying a roller that works in a slot in the side wall of the base-plate, by which the said tube is guided evenly and friction overcome, and projecting from or attached to said collar is an index finger that moves over a scale secured to the base-plate, by which the pressure of the steam is always measured or indicated. The spindle of the collar also 55 carries another roll that moves in the slot of a pivoted arm or lever fulcrumed to the vertical side portion of the bed-plate, and which pivoted arm or lever is provided with a series of perforations or openings, by which such varying 60 connections to the damper or valve-rod may be effected as that such damper or valve may be perfectly regulated, so as to maintain such uniformity of draft and consequent pressure of steam as may be desired in operation. 65

Reference being had to the several parts by the letters marked thereon, A represents the bed-plate, having to one side thereof a vertical portion, B, formed with a vertical slot or opening, C, (shown in dotted lines, Fig. 1,) 70 and secured to the bed-plate, at each side thereof, is a post, D, supporting between them at the top a cross-head or plate, E. Fitted in an opening, α , in the bed-plate, about centrally of the posts, is a stationary hollow tube, F, open 75 at the top and communicating at its bottom in the manner shown with the steam-pipe G; and surrounding this said vertical stationary tube is a vertically-moving tube, H, that is closed at its top by a screw-cap, I, having projecting upwardly therefrom a stem, K, around 80 which is coiled a spring, L, exerting a pressure between said screw-cap I and the cross-head or plate E, so as to normally maintain the vertically-moving tube down upon the bed-plate. Secured to the bed-plate, alongside of the tubes, is a gage, L', having thereon a scale indicating the pounds' pressure of steam entering the tubes from the boiler and surrounding 85 the vertically-moving tube is a close-fitting collar having fitted thereto an index-finger, M, that moves over said scale, thus indicating the pressure. This close-fitting collar N is also provided or formed with a spindle, b, carrying a small roller, c, that fits and works 90

within the slot C of the vertical side wall, B, of the bed-plate A, thus acting to evenly guide the said tube as well as to reduce friction.

Secured to the side portion, B, of the bed-plate by means of a bolt, d, is a movable lever, O, bent in the manner shown, and having in its shorter arm an elongated opening or slot, e, and in its longer arm a series of perforations or openings, f, by which attachment or connection may be had with the valve or damper rod in such varying manner as to allow of the valve or damper to be perfectly controlled in proportion to the pounds' pressure of steam acting to actuate said arm or lever through the movement of the movable outer tube. In the said slot e of this movable arm or lever O a small roller, g, works, which roller is carried by the spindle b of the collar N in like manner as the roller e; and it is evident that as the vertically-moving tube rises against the pressure of the spring L the said pivoted arm or lever O will be turned on its fulcrum, and thereby operate the valve or damper to which it is connected in any ordinary well-known manner.

From the foregoing description it will be seen that the vertically-moving tube is normally held down upon the bed-plate by the tension of spring L, and that as soon as the pressure to which the device has been set is overcome the pivoted arm or lever will be operated, in an obvious manner, to regulate the damper or valve with which it is supposed to be in connection. It will further be seen that by reason of the collar N moving with the tube the index-finger M thereof, by moving over the scale on the gage, will always indicate or measure the pressure.

It will be observed that the movable lever O is slightly bent, and that the position of its fulcrum is such as to bring it to an angle with the vertically-moving tube, which form and arrangement are necessary in order to obtain a movement of the valve corresponding to the movement of the sleeve.

Having thus described my invention, what I claim as new, and desire to secure by Letters Patent, is—

1. In a combined steam-pressure gage and draft-regulator, the combination, with a stationary tube secured to a suitable bed-plate, of a vertically-moving tube surrounding the same, having a screw-cap formed or provided with a stem, a spring tending to maintain said tube in a downward position, and a pivoted arm or lever actuated by said movable tube to close or regulate a damper or valve, the same

being slightly bent and at an angle to the tubes, substantially as described.

2. In a combined steam-pressure gage and draft-regulator, the combination, with a stationary tube open at its top and communicating at its bottom with the boiler, and a vertically-moving tube surrounding the same, closed at its top and maintained downwardly by a spring, of a collar surrounding said movable tube, at or near its bottom, and provided with an index-finger and a gage over which said index-finger moves, substantially as described.

3. In a combined steam-pressure gage and draft-regulator, the combination, with the bed-plate A, having to one side thereof a vertical portion, B, formed with the slot or elongated opening C, of the inner stationary tube fitted to said bed-plate, the outer movable tube provided with the screw-cap, from which projects a stem surrounded by a spring, the arm or lever pivoted to said side portion and provided with slot e, and the collar N, fitted to the movable tube and carrying the rollers g and e, moving in the slots of the side portions, B, and the said movable lever, substantially as described.

4. In a combined steam-pressure gage and draft-regulator, the combination, with the inner stationary tube and the outer movable tube normally held downward by a spring, of the gage L and the collar N, fitted to said movable tube and formed or provided with an index-finger, substantially as described.

5. In a combined steam-pressure gage and draft-regulator, the combination, with the bed-plate having the side portion formed with a vertical slot or opening, of the inner stationary tube, the outer movable tube normally held downward by a spring, and the collar N, having a spindle provided with a roller working in the slot of said side portion, substantially as described.

6. In a combined steam-pressure gage and draft-regulator, the combination, with the bed-plate having slotted side portion and the vertically-moving tube, of the movable arm or lever pivoted to said side portion, and the collar fitted to said movable tube and provided with a roller working in the slot of said pivoted arm or lever, substantially as shown, in the manner described.

In testimony whereof I have hereunto set my hand in the presence of two subscribing witnesses.

MOSES WILKES.
